UNITED STATES PATENT OFFICE

104,548

DESIGN FOR A KEY HOLDER

George A. Benker, Providence, R. I.

Application March 25, 1937, Serial No. 68,398

Term of patent 7 years

To all whom it may concern:

Be it known that I, George A. Benker, a citizen of the United States, residing at Providence, in the county of Providence and State of Rhode Island, have invented a new, original, and ornamental Design for a Key Holder, of which the following is a specification, reference being had to the accompanying drawing forming a part thereof.

Fig. 1 is a side elevation of one side;

Fig. 2 is an edge view; and

Fig. 3 is a side elevation of the other side of a key holder showing my new design, the dominant part being shown in full lines.

I claim:

The ornamental design for a key holder, substantially as shown and described.

GEORGE A. BENKER.
